LACE TABLECLOTH

Ferdinand P. Otto, Philadelphia, Pa., assignor to Quaker Lace Company, Philadelphia, Pa.

Application July 14, 1950, Serial No. 11,193

Term of patent 7 years

(Cl. D92—26)

To all whom it may concern:

Be it known that I, Ferdinand P. Otto, citizen of the United States of America, residing at Philadelphia, in the county of Philadelphia and State of Pennsylvania, have invented a new, original, and ornamental Design for a Lace Tablecloth, of which the following is a specification, reference being had to the accompanying drawing, forming a part thereof in which the figure is a face view of a slightly more than quarter section of the lace tablecloth showing my new design, the other three sections being identical with the quarter here disclosed, arranged in proper relation to complete the lace tablecloth. The section disclosed is shown over a dark background to bring out the details of the lace design.

I claim:

The ornamental design for a lace tablecloth, substantially as shown and described.

FERDINAND P. OTTO.
